(57) **CLAIM**

The ornamental design for a water heater top, as shown and described.

DESCRIPTION

FIG. 1 is a front elevation view of the top portion of a water heater according to the present invention;

FIG. 2 is a side elevation view of the water heater illustrated in FIG. 1;

FIG. 3 is a rear view of the water heater illustrated in FIG. 1; and,

FIG. 4 is a top plan view of the water heater illustrated in FIG. 1.

The outermost broken lines immediately adjacent the stippled areas represent the bounds of the claimed design while all other broken lines are for illustrative purposes only; none of the broken lines form a part of the claimed design.
